LEATHER POLISHING APPARATUS

Milford A. Buckley, Olean, N. Y., assignor to Carley Heater Company, Inc., Olean, N. Y., a corporation of New York

Application December 30, 1935, Serial No. 56,829

5 Claims. (Cl. 149—15)

The present invention relates to leather polishing apparatus.

A primary object of the present invention is the provision of a leather polishing apparatus which is simple and inexpensive in construction, and which is efficient and speedy in operation.

A further object of the invention is the provision of a leather polishing apparatus which comprises a polishing roll, a conveyor or feed roll, and a kick-off brush cooperating with the polishing roll; and separate adjustable driving means for the polishing roll, the feed roll, and the kick-off brush.

A still further object of the invention is the provision of a leather polishing apparatus comprising a power-driven polishing roll, an adjustable power-driven feed roll for presenting leather to the polishing roll, and a chute for returning the polished leather to the operator.

20 A still further object of the invention is the provision of a leather polishing apparatus comprising cooperating polishing and feed rolls which are of improved construction for assuring accurate feed of the leather as well as a uniform finish to the surface thereof. A still further object of the invention is the provision of a leather polishing apparatus embodying novel cooperating elements to secure uniformity of polish on the leather and adjustable means for varying the 30 degree of polish.

The invention consists in the improvements hereinafter described and claimed.

In the accompanying drawings, forming a part of this specification:

35 Figure 1 is a front elevational view of a preferred embodiment of the present invention;

Figure 2 is a left-hand end elevation; and

Figure 3 is a right-hand end elevation of the construction illustrated in Figure 1.

40 The same numerals of reference are used to designate like and corresponding parts in the various figures on the drawings.

The frame by which the various operating and driving elements are supported may be constructed of relatively heavy wood pieces or it may be constructed of angle-iron. The frame as illustrated is constructed of the former and comprises vertical corner posts 10, top, intermediate, and bottom horizontal end supports 11, 12 and 13, respectively, at the opposite ends of the frame, and a horizontal support 14 connecting opposite corner posts at each side of the frame intermediate the top and bottom thereof. The frame further comprises a pair of horizontal supports 15 interconnecting the opposite end supports 11 ad-

jacent the longitudinal center of the frame, and a like support 16 interconnecting the opposite end supports 13 intermediate the sides of the frame. The frame also includes opposite end vertical supports 17 and a vertical support 18 between the opposite ends of the frame.

The numeral 19 designates a polishing roll which, in accordance with the invention, is preferably constructed of woolen disks as indicated in Fig. 1, each of the discs preferably being constructed of small pieces of sample wool as is indicated in Fig. 3, the discs being fastened to a wood core as indicated at 20 in Fig. 3. The polishing roll may, however, be constructed of wool cloth suitably secured to the shaft later referred to.

The roll 19 is supported by a shaft 21 which at one end thereof is journalled in a bearing 22 and which inwardly of the opposite end thereof is journalled in a bearing 23. Each of the bearings 20 22 and 23 is adjustably supported on the threaded studs 24 projecting downwardly from a bearing-supporting bracket 25 which is suitably secured to the supports 15. The bearings 22 and 23 can readily be adjusted upon proper turning of the nuts 26 on the studs 24 whereby the polishing roll 19 can be properly adjusted with respect to the feed roll, later described, as may be occasioned as the surface thereof becomes worn.

The shaft 21 extends beyond the bearing 23 and 30 has suitably secured thereto externally of the frame a belt-wheel 27 which is operatively connected by a pair of V-belts 28 with a smaller belt-wheel 29 which is carried by the outer end of the shaft 30 of a motor 31, supported on a suitable 35 base 32.

The motor 31 is preferably of three (3) horse power and has sufficient velocity to drive the roll 19 at a velocity of substantially 850 revolutions per minute.

40 In order to provide sufficient driving tension in the belts 28 as well as to provide for easy replacement thereof the motor base 32 is preferably adjustably mounted in the frame which may be of any suitable construction and which as illustrated 45 preferably comprises guide-ways 33 in one of the rear corner posts 14 and in the support 18, in which guide-ways are slidably disposed guides 34 on the base 32, the base being secured in any adjusted position by means of nuts 35 engaging 50 studs 36 projecting through elongated slots 37 in the base 32.

The roll 19 is adapted to polish the surface of the leather which is presented thereto upon a suitable table 38 having an opening 39 therein to 55

permit the polished leather to follow the chute, later described, as well as to provide operating space for the propelling or feed roll 40.

The feed roll is mounted vertically below the 5 polishing roll 19 and is co-extensive in length therewith. The feed roll preferably comprises a cork-covered cylinder suitably secured to a shaft 41 which, at opposite ends thereof, is journaled in bearings 42, each of which is supported by a base 43 slidably disposed in a guide-way 44 in one 10 of the supports 17. Secured to the right hand end of the shaft 41 exteriorly of the frame is a relatively large sprocket-wheel 45 in driving engagement with a roller-chain 46, which chain engages 15 a small idling sprocket 47 and is driven by a small sprocket 48 fixed on the shaft 49 of a motor 50.

The motor 50 need only be of about three quarter horse power to drive the feed-roll, which has a velocity of only about ten (10) revolutions per 20 minute.

The feed-roll 40 is adapted to be raised and lowered in the operation of the machine, and this is effected by means of improved mechanism which not only raises and permits lowering of 25 the roll but provides for an adjustable uniform pressure on the leather being polished. The roll 40 is manually raised by means of a foot-treadle 51 comprising a longitudinally disposed slat 52 supported adjacent each end thereof by one end 30 of a bar 53 whose opposite or inner end is pivotally connected at 54 to an ear 55 projecting downwardly from the support 16. Pivotally connected at 56 to the support 16 adjacent each end thereof is a bell-crank lever 57, one arm of which is 35 pivotally connected at 58 to an adjustable link 59 and the other arm of which is pivotally connected at 60 to one end of a link 61 whose opposite end is pivotally connected at 62 to the adjacent bar 53 outwardly of the pivotal connection 40 54. The links 59 are pivotally connected at 63 to the respective bearings 42.

This construction provides a simple and efficient means for raising the feed roll 40 into engagement with the leather as it is pushed forward 45 on the table 38 for compressing same between the rolls 19 and 40 and feeding same forward during the polishing action of the roll 19.

A coil spring 64 is preferably connected with the treadle and the frame, as indicated in Fig. 3, 50 to normally hold the feed roll in inoperative position.

In order to provide a uniform pressure on the leather being polished an adjustable stud 65 is carried by the slat 52 adjacent each end thereof 55 and is adapted to engage a stop 66 when the feed roll is fully elevated, as is illustrated in Fig. 3. The studs 65 are provided with adjusting and securing nuts 67 and 68. In order to effect further adjustment of the feed roll the adjustable links 59 may be shortened or lengthened. 60 These adjustments in the feed roll actuating means further provide for varying the pressure on the leather for effecting different degrees of polish as may be desired on different grades of 65 leather.

When the feed roll is in lowered or inoperative position the chain 46 will be slack and in order 70 to provide sufficient driving tension in the chain when the feed roll is in raised operative position the idling sprocket 47 is carried by a block 69 vertically movable in a guide 70 in a bracket 71 disposed on the right-hand support 12, the block being retained in adjusted position by means of a bolt 72.

75 In order to prevent adherence of the leather to

the roll 19 as well as to deflect the same toward the return chute, later described, a kick-off brush 73 is provided.

The rotary brush 73 is carried by a spindle or shaft 74, which shaft is journaled at opposite 5 ends thereof in bearings 75 fixed to opposite end supports 12.

Secured to the shaft 74 inwardly of the adjacent end of the frame is a belt-wheel 76 operatively engaged by a pair of V-belts 77 which engage and are driven by a smaller belt wheel 78 fixed to the shaft 21 inwardly of the main drive belt-wheel 27 carried thereby.

In order to provide sufficient driving tension in the belts 77 the same are engaged by an idle roll 15 79 suitably journaled on a block 80 vertically movable in a guide-way 81 in a bracket 82, the block being retained in adjusted position by means of a bolt 83.

In order to protect the operator against injury from flying particles from the roll 19 as well as the roll itself, a sheet metal guard 84 is suitably secured at the upper edge thereof as by hinging to one of the supports 15, as indicated at 25 85 in Fig. 1, and securing the lower edge there- 20 of in slightly spaced relation to the table 38 by brackets 86.

The invention comprises an improved means for returning the polished leather to the operator and which, in a preferred form, comprises 30 a sheet metal chute 87 which is preferably secured at the upper edge thereof to one of the supports 15, as indicated at 88, and which is suitably secured at the lower edge thereof to a longitudinally-disposed strip 89 adjacent the slat 35 52 of the treadle 51.

The chute 87, as is clearly illustrated in Figs. 2 and 3, is concaved toward the operator and has sufficient inclination to permit the polished leather to fall by gravity to the feet of the operator. The chute 87 is co-extensive in width with the length of the rolls 19 and 40 as well as the brush 73, and is preferably provided with lateral 40 guide-flanges 90. In the operation of the construction disclosed the leather is placed upon the table 38, whereupon the operator presses the treadle 51 down until the studs 65 engage the stops 66, and the feed roll 40 will, through the linkage above described, be brought into engagement with the leather and will compress same 45 against the polishing roll 19 and feed the same uniformly toward the kick-off brush 73. The kick-off brush will release the leather from the roll 19, whereupon it will fall onto the chute 87 and return to the operator.

The cork-covered feed roll is not only yieldable but affords sufficient frictional engagement with the leather to uniformly and consistently feed the same forward, and the woolen disc polishing-roll presents a highly effective finishing surface to 60 the leather being treated. As the feed roll rotates only about ten (10) revolutions per minute while the polishing roll rotates about eight hundred and fifty (850) revolutions per minute or eighty-five (85) times as fast as the feed roll, the surface of 65 the leather will be subjected to an effective polishing action by the roll 19.

From the foregoing description, it will be seen that the improved machine in accordance with the present invention is highly efficient in operation 70 as well as being capable of polishing leather rapidly, and that the machine embodies such adjustments as to assure such efficiency in operation even after long periods of use.

While I have disclosed a single specific em- 75

bodiment of my invention, nevertheless it is to be understood that the same is to be considered as illustrative and not restrictive, the scope of the invention being defined in the subjoined claims.

5. What I claim and desire to secure by U. S. Letters Patent is:

1. Leather polishing apparatus comprising a rotatable polishing roll, a rotatable feed roll for cooperation with the polishing roll, a rotary brush 10 cooperating with the polishing roll for deflecting therefrom the leather being polished, a pair of power units, drive means for the polishing roll and rotary brush jointly driven by one of said power units, drive means for the feed roll driven 15 by the other of said units, and means for adjusting the tension in all of said drive means.

2. Leather polishing apparatus comprising a rotary polishing roll having a drive shaft, a rotary brush having a drive shaft, a pair of belt pulleys 20 fixed to the polishing roll shaft, a belt pulley fixed to the rotary brush shaft, a motor having a belt pulley fixed to the drive shaft thereof, flexible drive means operatively associated with the belt pulley on the motor and one of said belt pulleys 25 on the polishing roll drive shaft, flexible drive means operatively associated with the other of said belt pulleys on the polishing roll drive shaft and the belt pulley on said brush drive shaft, and means individual to said flexible drive means for 30 adjusting the tension thereof.

3. Leather polishing apparatus comprising a polishing roll and a feed roll for continuously presenting leather to the polishing roll, said polishing roll having an operating surface formed 35 of wool and said feed roll having an operating surface formed of cork.

4. Leather polishing apparatus comprising a frame, a horizontal table supported by the frame intermediate the top and bottom thereof and having an opening therein, a polishing roll and a cooperating kick-off brush each rotatably mounted above the table, a feed roll rotatably mounted below the table in vertical alinement with the polishing roll and projecting through the opening in said table, means for driving the polishing roll, the kick-off brush and the feed roll, said 10 polishing roll being rotatably journaled in bearings adjustably supported by brackets depending from the top of said frame, and said feed roll being rotatably journaled in bearings slidably mounted in said frame below said table, and 15 means for successively positioning the feed roll in operative and inoperative relation with the polishing roll.

5. Leather polishing apparatus comprising a frame, a horizontal table supported by the frame 20 intermediate the top and bottom thereof and having an opening therein, a polishing roll and a cooperating kick-off brush each rotatably mounted above the table, a feed roll rotatably mounted below the table in vertical alinement with the 25 polishing roll and projecting through the opening in said table, means for driving the polishing roll, the kick-off brush and the feed roll, said feed roll driving means comprising a power unit, a chain operably engaged with said feed roll and 30 said power unit, an adjustably mounted idler sprocket engaging said chain, and means for successively positioning the feed roll in operative and inoperative relation with the polishing roll.
